LATCHING MECHANISM

Willard T. Parker, Wilkinsburg, Pa., assignor to Westinghouse Electric & Manufacturing Company, East Pittsburgh, Pa., a corporation of Pennsylvania

Application December 1, 1937, Serial No. 177,601

13 Claims. (Cl. 200—109)

The invention relates to circuit breakers in general and more particularly to latching mechanisms for circuit breakers.

An object of the invention is the provision of an improved latching mechanism for a circuit breaker that is simple, reliable in operation, and inexpensive to manufacture.

Another object of the invention is the provision of a latching mechanism for releasably holding the contact members of a circuit breaker in closed position, that requires fewer parts than has heretofore been considered necessary for breakers of the same or comparable size and rating.

15 Another object of the invention is the provision of an improved latching mechanism for a circuit breaker that offers a relatively small resistance to relatching of the breaker actuating means and yet which is capable of positively holding the breaker closed against the force of a powerful opening bias.

Another object of the invention is the provision of a circuit breaker of the trip free type with an improved latching mechanism that offers a very small resistance to the retrieving of the breaker actuating means to its latched position thus permitting the use of less powerful retrieving springs to insure retrieving, and also reducing the total energy required to reclose the breaker.

30 The novel features that are considered characteristic of the invention are set forth in particular in the appended claims. The invention itself, however, both as to structure and operation, together with additional objects and advantages thereof will be best understood from the following detailed description of one embodiment thereof when read in connection with the accompanying drawings in which:

Figure 1 is a view partly in side elevation and partly in section illustrating the latching mechanism constructed in accordance with the invention as applied to the operating mechanism of a circuit breaker.

Fig. 2 is a plan view of the latching mechanism in conjunction with the trip free elements of the actuating mechanism of the breaker.

Fig. 3 is a sectional view taken substantially along the line III—III of Fig. 2 showing the latching mechanism in latching position.

45 Fig. 4 is a fragmentary sectional view similar to Fig. 3 illustrating the latching mechanism at a stage of the tripping operation immediately following release of the actuating means.

Fig. 5 is a fragmentary sectional view similar 55 to Fig. 4 illustrating the latching mechanism at

a stage of the retrieving operation of the actuating means; and,

Figs. 6 and 7 are fragmentary side elevational views illustrating the levers of the actuating means in the tripped and retrieved positions respectively.

The present invention constitutes an improvement and further development of the mechanism disclosed in the copending application of J. B. MacNeill and John W. May, Serial No. 79,670 which is assigned to the assignee of this invention.

Referring to the drawings and particularly Figure 1 thereof, the latch mechanism, indicated generally at 9, is shown mounted in operative position on an operating mechanism 11 of a circuit breaker.

The operating mechanism 11 is of the same general construction as the operating mechanism shown and described in the above mentioned copending application of J. B. MacNeill and John W. May, and comprises, in general, a frame 13 on which is mounted an operating electromagnet 15, and a trip-free lever mechanism indicated generally at 17 which normally serves to connect the circuit breaker (not shown) to the operating electromagnet 15.

The operating electromagnet 15 is in the form of a solenoid and comprises a movable core 19, a cooperating stationary core (not shown) and an operating winding 21, which, when energized, pulls the movable core downwardly toward the stationary core to effect a closing operation of the circuit breaker.

The trip-free lever mechanism comprises a pair of spaced parallel and rigidly connecting operating levers 23 pivoted on the frame 13, and a pair of spaced parallel and rigidly connected actuating levers 25 which are pivoted to the free ends of the operating levers 23. The operating levers 23 are rigidly connected together by means of a brace 27 extending between the levers adjacent their lower edges. The operating levers 23 are pivoted for rotation on the frame 13 by means of a pair of pivot pins 29 (Fig. 2).

The actuating levers 25 are pivotally connected adjacent their one end to the free ends of the operating levers 23 by means of a pivot pin 31 which extends transversely through the ends of the levers 23 and 25. The levers 25 are rigidly connected together by means of a brace 33 which extends between the levers, and the levers 25 are spaced so as to be movable into the space between the outer operating levers 23.

The contact members (not shown) of the cir-

cuit breaker are connected through a rod 35 to the actuating levers 25 intermediate their ends by means of a pivot pin 37 which extends between the levers 25. The actuating levers 25 carry a trip-free bar or roller 39 which extends transversely between the free ends of the levers 25 and which is adapted to be normally engaged by the latching mechanism 9 as will be explained hereinafter.

10 When in the closed circuit position shown by the full lines in Fig. 1, the operating levers 23 are biased for movement in a clockwise direction about their pivot axis 29 by means of a retrieving spring 41 positioned between the levers 23 and the frame 13. One end of the spring 41 is pivotally anchored by means of a bracket 43 to the levers 25 while the other end of the spring abuts the end of the frame 13 and is maintained in that position by any suitable means.

15 A latch member 45 is pivotally carried by the frame 13 and is biased by means of a spring 47 to a latching position for engaging the pivot pin 31 which connects the ends of the levers 23 and 25 to retain them in the closed circuit position shown in the full lines in Fig. 1. In order to cause the latch 45 to release the pivot pin 31 and the operating levers 23 during a tripping operation of the mechanism, the actuating levers 25 carry a projection 49 adjacent the pivot pin 31 for engaging a cooperating projection 51 carried by the latch 45. As the actuating levers 25 move to the position shown by the dotted lines in Fig. 1 under the influence of the opening bias of the breaker, following their release, the projection 49 carried thereby engages the cooperating projection 51 and moves the latch member 45 to its released position causing the latch 45 to release the pivot pin 31 and the free ends of the operating levers 23. The reactive force of the compressed retrieving spring 41 then rotates the operating levers 23 in a cooperating direction about their pivot axis 29 to the open circuit position shown by the dotted lines in Fig. 1. During this movement of the operating levers 23, the actuating levers 25 are rotated by the operating levers 23 in a clockwise direction about the pivot pin 37 which has reached the upper limit of its movement when the breaker has reached its full open circuit position. The clockwise rotation by the operating levers 23 returns the free ends of the actuating levers 25 and the trip-free bar or roller 39 to their latched position as shown in Fig. 7, to be reengaged and latched by the latching mechanism 9. The actuating levers 25 are thus automatically retrieved to their latched position following each release thereof.

In order to actuate the mechanism to a closed circuit position, the operating levers 23 are connected to the movable core 19 of the operating electromagnet 15 by means of a pivot link 52 which is pivotally connected at its lower end to the movable core 19 by means of a pivot pin 53. The upper end of the link 52 is pivotally connected to the operating levers 23 intermediate their ends by means of a pivot pin 55.

When the electromagnet 15 is energized, the movable core 19 and the connecting link 52 are moved downwardly to rotate the operating levers 23 and the connected actuating levers 25 in a counterclockwise direction about the pivot pins 29 and the trip-free roller 39, respectively from the position shown in Fig. 7 to the closed circuit position shown in the full lines in Fig. 1 of the drawings.

75 When the free ends of the actuating levers 25

and the trip-free roller 39 are held in latched position by the latching mechanism 9, the axis of the roller 39 which forms the normal pivot axis of the actuating levers 25 is aligned with the axis of the pivot pins 29 which form the pivot axis of the operating levers 23 and the latch serves as a fulcrum point for the actuating levers 25 to connect the breaker to the operating levers 23 for operation thereby.

The brace 27 which connects the operating levers 25 serves as a stop to prevent movement of the actuating levers 25 below the operating levers 25 during the retrieving operation and to cause the trip free roller 39 to align with the pivot pins 29 when the levers are in the position shown in Fig. 7.

The latch mechanism 9 comprises a main latch member 57 biased to a latching position in which it engages and restrains the trip-free roller 39 and the actuating levers 25 in latched position shown in Fig. 3 and in the full lines as shown in Fig. 1. The latch member 57 is pivotally carried on the frame 13 by means of a pivot pin 59 and is biased to its latching position by means of a compression spring 61 interposed between the latch member 57 and a cross piece 63 of the frame 13. The ends of the spring 61 are seated in suitable cylindrical recesses or wells (not shown) provided in the latch member 57 and the cross piece 63. The cross piece 63 has a surface 64 which forms a stop to prevent movement of the latch 57 beyond its latched position as shown in Fig. 4.

In order to hold the latch 57 in its latching position against the upward bias produced on the actuating levers 25 by the bias of the circuit breaker, a second latch member in the form of a lever 65 is provided. The second latch member 65 is pivotally mounted at one end of the frame 13 by means of a pivot pin 67. The inner end of the second latch member 65 is provided with a substantially right angle notch 69 for engaging a cooperating surface 70 on the main latch 57 to hold the main latch in its latching position. It will be noted that the point of engagement of the second latch 65 with the latch 57, and the pivot axis of the latch 65 in the latching position thereof lie in a line which is substantially at right angles to the direction of movement of the main latch 57 so that the latch member 65 alone in its latching position effectively locks the main latch 57 in its latching position. The latch member 65 is biased to its latching position by means of a light coil compression spring 71 which exerts a very small force on the second latch member for returning it to its latched position during resetting of the latching mechanism.

The second latch member 65 is adapted to be moved to its released position to effect a tripping operation of the latching mechanism and operating mechanism by a tripping means indicated generally at 73. The tripping means 73 is carried by the frame 13 and comprises a tripping electromagnet 75 including a movable core 77. The tripping electromagnet 75 is adapted to be energized in response to predetermined abnormal conditions to move the movable core 77 in an upward direction during which movement it strikes the second latch member 65 and moves it to released position to effect release of the main latch member 57 and tripping of the operating mechanism and circuit breaker.

The movable core 77 of the tripping electromagnet is also adapted to be actuated in an upward direction manually by the operation of a

manually operated lever 79 pivotally carried on the frame 13. The end of the manual tripping lever 79 is adapted to engage an intermediate member 81 which is slidably mounted on a guide bolt 83. The intermediate member 81 is also guided by means of a pair of guide members 85. The intermediate member 81 is moved by the manual tripping lever 79 in an upward direction to engage and move the movable core 77 upwardly to effect tripping of the latch mechanism and operating mechanism in the same manner as when the electromagnet 75 is energized.

The main latch 57 has its upper surface rounded as indicated at 87 to provide a cam surface for cooperating with the trip-free roller 39 during the retrieving movement thereof. As the trip-free roller 39 is moved downwardly to its latched position during a retrieving operation, it engages the rounded cam surface 87 of the latch member 57 and forces the latch member 57 in a clockwise direction about its pivot axis 59 to released position as shown in Fig. 5, thus allowing the trip-free roller to clear or move below the nose of the latch 57. When the trip-free roller 39 reaches its latched position, the biasing spring 61 returns the latch member 57 to its latching position to reengage the roller 39.

To insure complete retrieving of the actuating levers 25 and the trip-free roller 39 to latched position, it is necessary that the second latch member 65 be maintained in its released position free of the main latch member 57 until the actuating levers 25 and trip-free roller 39 are retrieved to their latched position. Otherwise, the trip-free roller 39 would jam against the top of the main latch member 57 during a retrieving operation.

For holding the second latch member 65 in its released position free of the main latch 57 during release and retrieving of the actuating levers 25 and the trip-free roller 39, there is provided a lever 89 which is pivoted on the pivot pin 67 of the second latch member 65. The lever 89 consists of two arms 91 and 93 (Fig. 2) which are rigidly connected for movement together by means of a pin 95. The ends of the arms 91 and 93 are in pivotal engagement with the pin 67. The arm 91 of the lever 89 is of greater length than the arm 93 and has a projecting portion 96, the end 97 of which is bent inwardly so as to lie in the path of the final retrieving movement of one of the actuating levers 25 so as to be engaged thereby during the final retrieving movement and in the retrieved position of the actuating lever 25. The lever 89 is biased in a clockwise direction by means of a light coil compression spring 99 which is interposed between the cross pin 95 and the frame 13. The lever 89 is held in inoperative position by the actuating levers 25 when the actuating levers are in their latched position as shown in Fig. 3 to allow the second latch member 65 to engage and hold the main latch member 57 in its latched position. When the latching mechanism 9 is operated by the tripping means 13 to release the trip-free roller 39 and the free ends of the actuating levers 25, the free ends of the levers 25 move in an upward direction and disengage the lever 89. The lever 89, when disengaged by the actuating levers, is moved in a clockwise direction about its pivot axis 67, and the cross pin 95 thereof engages and holds the second latch member 65 in its released position as shown in Figs. 4 and 5. The biasing spring 99 is of sufficient strength to cause the lever 89 to hold the second latch member 65 in its re-

leased position against the bias of the return spring 71.

During retrieving of actuating levers 25 after the trip-free roller has substantially cleared the nose of the latch member 57, the end of one of the actuating levers 25 engages the inwardly bent end 97 of the lever 89 and forces the lever 89 in a counterclockwise direction about its pivot axis 67 to an inoperative position allowing the second latch member 65 to be returned to its latching position in engagement with the main latch member 57 by means of the return spring 71.

Since the second latch member 65 in its latching position is alone sufficient to hold the main latch 57 in latching position to hold the breaker 15 closed against its bias, the biasing spring 61 of the latch 57 need only be strong enough to exert sufficient force to return the latch member 57 to its latching position with the required speed, and since the biasing spring 99 of the holding lever 89 need only be strong enough to hold the second latch member 65 in its released position against the bias of its light return spring 71, the springs 61 and 99 offer only a very small resistance to the return or the retrieving movement of the actuating levers 25. This permits the use of a smaller and less powerful retrieving spring for causing retrieving of the actuating levers, and thus reduces the total amount of energy required for operating the mechanism to close the circuit breaker.

The operation of the mechanism is briefly as follows: With the mechanism in the closed and latched position as shown in full lines in Fig. 1, the operation of the tripping means 13, either in response to predetermined electrical conditions or by the manual operating lever 79 lifts the movable core 77, causing it to strike and move the second latch member 65 to its released position as shown in Fig. 4. The movement of the second latch member 65 to its released position releases the main latch member 57 and since this member alone is insufficient to hold the mechanism and breaker in closed position, the inner actuating levers 25 are rotated in a counter-clockwise direction by the bias of the breaker, forcing the main latch member 57 to its released position. As the free ends of the actuating levers 25 move upwardly, they disengage and release the biased lever 89, allowing the lever to move in a clockwise direction to engage and hold the second latch member 65 in its released position. The actuating levers 25 are rotated by the biasing action of the breaker to the position shown in Fig. 6 and by the dotted lines in Fig. 1. At this point the breaker is in full open position. During upward movement of the actuating levers 45 the projection 49 carried thereby moves the latch member 45 to released position releasing the free ends of the operating levers 23. When released, the operating members 23 are moved in a clockwise direction about their fixed pivot axis 29 by the retrieving spring 41 to the open circuit position shown in Fig. 7 and by the dotted lines in Fig. 1. The upward movement of the operating levers 23 causes the actuating levers 25 to be rotated in a clockwise direction about the pivot pin 37 to the retrieved position shown in Fig. 7. During the retrieving movement of the actuating levers 25, the trip-free roller 39 is moved to its latched position and is reengaged by the main latch member 57. As the trip-free roller approaches its latched position and clears the main latch 57, the free end of one of the actuating levers 25 engages and moves the latch holding lever 89 to its inoperative position 75

allowing the second latch member 65 to return to its latching position in holding engagement with the main latch member 57.

To close the breaker, the operating electromagnet 15 is energized to pull the movable core 19 and connecting link 52 downwardly. The downward movement of the core 19 and the connecting link 52 rotates the connected operating levers 25 and actuating levers 23 in a counter-clockwise direction from the position shown in Fig. 7 to the position shown by the full lines in Fig. 1. As the levers 23 and 25 approach closed position the pin 31 forces the latch member 45 to its released position in clearing the same. When the levers 23 and 25 reach their fully closed position as shown in the full lines in Fig. 1, the latch member 45 is moved to its latching position by the spring 47 to hold the levers in closed position.

While the invention has been disclosed in accordance with the provisions of the patent statutes, it is to be understood that various changes may be made in the structural details thereof without departing from the spirit of the invention. It is desired, therefore, that the accompanying claims be given the broadest reasonable construction possible in the light of the prior art.

I claim as my invention:

1. In a latching mechanism for a circuit breaker provided with a biased actuating member releasable to effect opening of the circuit, in combination, a main latch biased to a latching position for engaging and restraining said actuating member in a predetermined position, a second latch having a latching position for holding said main latch in its latching position, said second latch being biased to its latching position, and a spring biased means controlled by said actuating member for maintaining said second latch in released inoperative position until said actuating member is returned to said predetermined position following each release thereof.

2. In a latch mechanism for a circuit breaker provided with an operating mechanism including a biased trip free member releasable to effect opening of the circuit, in combination, a main latch biased to a latching position for engaging and restraining said trip free member in a predetermined position, a second latch having a latching position for engaging and holding said main latch in latching position, said second latch being biased to its latching position, and a spring biased member controlled by said trip free member for maintaining said second latch in released inoperative position until said trip free member is returned to said predetermined position following each release thereof.

3. In a latching mechanism for a circuit breaker provided with a biased actuating member releasable to effect opening of the circuit, in combination, a main latch biased to a latching position for engaging and restraining said actuating member in a predetermined position, a second latch having a latching position for engaging and holding said main latch in latching position, said second latch being biased to its latching position, and a spring biased member engaged and held in an inoperative position by said actuating member in its predetermined position, said spring biased member being operable when released by said actuating member to maintain said second latch in released position until said actuating member is returned to its predetermined position.

4. In a latching mechanism for a circuit breaker provided with a biased actuating member

releasable to effect opening of the circuit, in combination, a main latch biased to a latching position for engaging and restraining said actuating member in a predetermined position, a second latch having a latching position in which it engages and holds said main latch in latching position, said second latch being biased with a relatively light force to its latching position, a spring biased member operable to hold said second latch in released position when the actuating member is released and until it is returned to said predetermined position, said spring biased member being engaged and moved by said actuating member to an inoperative position against its bias when said actuating member is returned to said predetermined position, the spring bias of said holding member being sufficient to hold said second latch in released position but offering only a small resistance to the return movement of said actuating member to said predetermined position.

5. In a latching mechanism for a circuit breaker provided with a biased actuating member releasable to effect opening of the circuit, in combination, a frame, a main movable latch biased to a latching position for engaging and restraining said actuating member in a predetermined position, a second movable latch having a latching position for engaging and holding said main latch in its latching position said second latch being biased to its latching position, tripping means operable to move said second latch to released position to effect release of said main latch and actuating member, and means carried by said frame and controlled by said actuating member for holding said second latch in its released position until said actuating member is returned to said predetermined position following each release thereof.

6. In a latching mechanism for a circuit breaker provided with a biased actuating member releasable to effect opening of the circuit, in combination, a frame, a main movable latch biased to a latching position for engaging and restraining said actuating member in a predetermined position, a second movable latch having a latching position for engaging and holding said main latch in its latching position said second latch being biased to its latching position, tripping means operable to move said second latch to released position to effect release of said main latch and actuating member, said actuating member when returned to its predetermined position forcing said main latch back to its released position to clear the same prior to being relatched thereby when it reaches said predetermined position, and means carried by said frame and controlled by said actuating member for holding said second latch in its released position clear of said main latch until said actuating member is returned to said predetermined position following each release thereof.

7. In a latching mechanism for a circuit breaker provided with a biased actuating member releasable to effect opening of the circuit, in combination, a main latch biased to a latching position for engaging and restraining said actuating member in a predetermined position, a second latch having a latching position for engaging and holding said main latch in its latching position said second latch being biased to its latching position, tripping means operable to move said second latch to released position to effect release of said main latch and actuating member, and a pivoted spring biased lever engaged and held in an inoperative position by said actuating member in its

predetermined position, said lever being operable when released by said actuating member as it moves away from its predetermined position to engage and hold said second latch in released position until said actuating member is returned to its predetermined position.

8. In a latching mechanism for a circuit breaker provided with a biased actuating member releasable to effect opening of the circuit, in combination, a main latch biased to a latching position for engaging and restraining said actuating member in a predetermined position, a second pivotally mounted latch having a latching position for engaging and holding said main latch in latching position, said second latch being biased with a light force to its latching position, tripping means operable to move said second latch to released position to effect release of said main latch and actuating member, and a lever pivoted about the same axis as the second latch and controlled by said actuating member for holding said second latch in released position until said actuating member is returned to its predetermined position following each release thereof.

9. In an operating mechanism for a circuit breaker, a trip free member releasable from a predetermined position to effect opening of the breaker, means for automatically returning said member to its predetermined position following each release thereof, operating means operable to close said breaker only when said member is held in said predetermined position, in combination, a main latch biased to a latching position for engaging and restraining said member in its predetermined position, a second latch having a latching position for engaging and holding said main latch in latching position, said second latch being biased to latching position, trip means operable to move said second latch to released position to effect release of said main latch and trip free member, and a spring biased member engaged and held in an inoperative position by said trip free member in its predetermined position said spring biased member being operable when released to engage and hold said second latch in released position until said trip free member is returned to its predetermined position to allow said trip free member to clear said main latch as it returns to said predetermined position.

10. In an operating mechanism for a circuit breaker, a trip free member releasable from a set position to effect opening of the breaker, means for automatically resetting said member to its set position following each release thereof, operating means operable only when said member is held in its set position to close the breaker, in combination, a frame, a main latch biased to a latching position for engaging and restraining said trip free member in its set position, a second latch having a latching position for engaging and holding said main latch in latching position, said second latch being biased to its latching position, trip means operable to move said second latch to released position to effect release of said main latch and trip free member, and means carried by said frame and controlled by said trip free member for holding said second latch in released position until said trip free member is

reset to its set position following each release thereof to allow said trip free member to clear said main latch during resetting of said trip free member.

11. In an operating mechanism for a circuit breaker, a trip free member releasable from a set position to effect opening of the breaker, means for automatically resetting said member to its set position following each release thereof, operating means operable only when said member is held in its set position to close the breaker, in combination, a main latch biased to a latching position for engaging and restraining said trip free member in its set position, a second latch having a latching position for engaging and holding said main latch in latching position, said second latch being biased to its latching position, trip means operable to move said second latch to released position to effect release of said main latch and trip free member, and a spring biased pivoted lever engaged and held in an inoperative position by said trip free member in its set position, said lever being operable when released by said trip free member as it moves away from set position, to engage and hold said second latch in released position until said trip free member is returned to its set position.

12. In an operating mechanism for a circuit breaker, a trip free member releasable from a set position to effect opening of the breaker, means for automatically resetting said member to its set position following each release thereof, operating means operable only when said member is held in its set position to close the breaker, in combination, a main latch biased to a latching position for engaging and restraining said trip free member in its set position, a pivoted second latch having a latching position for engaging and holding said main latch in latching position, said second latch being biased to its latching position, trip means operable to move said second latch to released position to effect release of said main latch and trip free member, and means including a lever pivoted about the same axis as said second latch and controlled by said trip free member for holding said second latch in released position until said trip free member is reset to its set position following each release thereof.

13. In a latching mechanism for a circuit breaker operating mechanism provided with a trip free retrieving actuating member releasable from a latched position to effect opening of the circuit and automatically resettable to its latched position following each release thereof, in combination, a main latch biased to a latching position for restraining said actuating member in latched position, a second latch having a latching position for holding said main latch in latching position, said second latch being biased by a light force to its latching position, and a spring biased member operable to hold said second latch in released position until said actuating member is returned to its latched position following each release thereof, said spring biased member being engaged and held in an inoperative position by said actuating member when in its latched position.

WILLARD T. PARKER.
